HYDRAULIC ACTUATED FIRING PIN FOR A FIREARM

Earle M. Harvey, Agawam, Mass., assignor to the United States of America as represented by the Secretary of the Army

Application August 13, 1954, Serial No. 449,812

3 Claims. (Cl. 42—69)

(Granted under Title 35, U. S. Code (1952), sec. 266)

The invention described herein may be manufactured and used by or for the Government for governmental purposes without the payment of any royalty thereon.

This invention relates to firing mechanisms for automatic firearms and more particularly to firing pins which are mounted for reciprocable movement in a breech member.

Difficulties are oftentimes encountered, when designing firing pins, because of the problems involving the length and weight thereof. It is important in designing firing pins that the weight be reduced so that the cartridge will be struck by as light a blow as possible, while still retaining sufficient strength in the structure to eliminate breakage. The matter of length is likewise important because by increasing the length of the firing pin the structure is increasingly subjected to fatigue during operation, causing fatigue cracks and resulting breakage.

Further, when mounting a firing pin in the breech member, it is necessary to provide unobstructed space therein axially rearward of the barrel, which is accomplished sometimes at the expense of other desirable design features. It is also difficult by conventional means to provide offset mounting for the firing pin when such is desired.

Accordingly, it is an object of this invention to provide a firing pin having a flexible column for circuiting obstructions in the breech member and for facilitating offset mounting.

It is another object of this invention to provide a firing pin wherein the weight is reduced considerably without sacrificing structural strength.

It is a further object of this invention to provide a firing pin wherein the length is extendable to any distance without undesirable effects.

It is a specific object of this invention to provide a firing pin actuatable by self-contained hydraulic means.

It is another specific object of this invention to provide a firing pin device wherein a cartridge striker member is separated from an actuator member by a cooperating, movement transmitting column of fluid.

The specific nature of the invention as well as other objects and advantages thereof will clearly appear from a description of a preferred embodiment as shown in the accompanying drawings in which:

Fig. 1 is a fragmentary, longitudinal, cross-sectional view of the rear end of the firearm showing the firing pin of this invention mounted in the breech mechanism thereof in one embodiment and in a firing position;

Fig. 2 is an enlarged view taken along line 2—2 of Fig. 1;

Fig. 3 is a longitudinal, cross-sectional view of the breech member showing the firing pin in another embodiment and in a retracted battery position;

Fig. 4 is an enlarged, fragmentary view of the embodiment illustrated in Fig. 3 but showing the firing pin in forward cartridge firing position; and

Fig. 5 is a longitudinal, cross-sectional view of still another embodiment of the firing pin of this invention.

Shown in the figures, is a firearm having a barrel 12 with a conventional cartridge chamber 14, a receiver 16 and a

breech mechanism 18. Breech mechanism 18 includes a carrier 20 mounted in receiver 16 for slidable movement between a recoil and a battery position and a bolt 22 mounted for limited slidable movement in such carrier as is disclosed in Patent No. 2,626,474 to John L. Lochhead.

Extending forwardly from the rear end of bolt 22 in Figs. 1, 2, 3 and 4 is a longitudinal bore 24 which is tapered at the front end, as noted at 21, to blend with a forwardly extending smaller diameter portion 23. In the embodiment illustrated in Fig. 5, bore 26 is offset to a lower level at the front end with taper portion 21 and smaller diameter portion 23 being contained in a plug 25 which is secured as by press fit in the front portion of such offset portion.

15 In the embodiments illustrated in Figs. 1, 2 and 5, a port 28 extends from the top side of bolt 22 to bore 24 to provide means of filling such bore with hydraulic fluid 59. Port 28 is counterbored from the top, as noted at 30, to form a shoulder 32 and such counterbore portion is 20 threaded to receive a screw 34. A gasket 36 is provided between shoulder 32 and screw 34 so that tightening screw 34 thereagainst makes port 28 fluid tight.

25 Mounted for slidable movement in the front end of bore 24 and smaller diameter portion 23 is a conventionally pointed cylindrical cartridge striker member 38 which is installed in the embodiment illustrated in Figs. 1 and 2 from the rear end, and in bore 26 illustrated in Fig. 5 from the front end with plug 25 installed after installation. Slidably mounted transversely through 30 cartridge striker member 38 is a retractor member 40 having an end 42 cooperably received in an arcuately terminated recess 44 in carrier 20 on one side of bolt 22 and an opposite end 43 similarly received in an arcuately terminated recess 45 in the carrier on the opposite side 35 of the bolt. A planar surface 41 extends longitudinally forward from arcuate recess 45. Provided on retractor 40, intermediate ends 42 and 43 is a cam surface 46 which is engageable with an angular surface 47 in cartridge 40 40 striker member 38. As taught by the aforementioned patent to John L. Lochhead, when bolt 22 is in battery position retractor 40 is moved by the engagement of end 42 thereof with the rear arcuate end of recess 43 so that cam surface 46 is moved away from angular surface 47, freeing cartridge striker member 38 for actuation by a hammer 56 to fire a cartridge 49 in chamber 14. During the ensuing recoil of breech mechanism 18, end 43 of retractor 40 cammingly engages the forward end of recess 45 and is moved thereby onto surface 41, whereby cam surface 46 engages angular surface 47 on cartridge striker member 38 for camming retraction thereof with the engagement of end 43 with surface 41 maintaining such retractor in a retracted position.

50 Slidably mounted in the rear end of bore 24 in Figs. 1, 2 and bore 26 in Fig. 5, is a cylindrical actuator member 48 which is provided with an annular groove 50. A pin 52 is transversely mounted through bolt 22 to be received by groove 50 for limiting the reciprocable movement of actuator 48 with such movement being sufficient to actuate cartridge striker member 38 to fire cartridge 49 when 55 transmitted thereto as hereinafter explained. Pin 52 is so arranged in bolt 22 that the rear end of actuator 48 extends rearwardly from bolt 22 to be engageable by hammer 56.

60 In the embodiment illustrated in Figs. 1, 2 and 5, there are fixedly secured to the facing ends of actuator 48 and cartridge striker member 38 cup-like hydraulic seals 57 and 58, respectively, or any other suitable type of seal which will maintain in bore 24 a column of hydraulic fluid 59, while being slidably moved therein. Whereby, such 65 column of hydraulic fluid 59 is responsive to reciprocal movement of actuator 48 and cartridge striker member 38 for actuation of the opposite one of such actuator or cartridge striker member.

In the embodiment illustrated in Figs. 3 and 4, the rear end of bore 24 is counterbored, as noted at 60, to receive as by press fit an insert 62. Provided in insert 62 is a passageway 64 which is longitudinally aligned with bore 24. A hole 88 provides outside communication with passageway 64 and such hole is counterbored from the top side of bolt 22 part way into insert 62 and is threaded to receive screw 34 which aids in securing insert 62 in bolt 22 as well as incloses such hole.

The front of passageway 64 is counterbored and threaded, as noted at 70, and such counterbore portion threadably receives a diaphragm member 72. The rear end of passageway 64 is counterbored, as noted at 73, and is arranged to threadably receive a diaphragm member 75 in the front portion with an actuator 92 mounted rearwardly thereof. A pin 78 is mounted transversely through insert 62 for cooperation with an annular groove 94 in actuator 92 to limit the reciprocation thereof.

Diaphragm members 72 and 75 are provided with axial holes 74 and 77, respectively, and fixedly secured to the facing ends of each of such diaphragm members are diaphragms 76 and 79, respectively. Diaphragms 76 and 79 are distensible in the area of holes 74 and 77 and form liquid tight seals to secure in passageway 64 the column of hydraulic fluid 59 which fills such passageway when diaphragm members 72 and 75 are tightened against the shoulders 83 and 84 formed, respectively, by the counterbores 70 and 73. The ends of holes 74 and 77, adjacent the associated diaphragms 76 and 79, are countersunk, as noted at 80, to permit deflection of the diaphragms for displacement of the column of hydraulic fluid 59 in passageway 64. The total of such displacement is the amount of the deflections of diaphragms 76 and 79 into their respective countersunk portions 80 and such displacement is arranged to be equal to the movement of actuator 92 permitted by pin 78 in groove 94.

Extending from the front end of actuator 92 is a stem portion 81 which is slidably received by hole 77 in diaphragm member 75 to engage diaphragm 79 for deflection thereof. Extending from the rear end of a cartridge striker member 98, which is similar to the aforementioned cartridge striker member 38, is a rod portion 82 which is slidably received by hole 74 in diaphragm member 72 for contact by diaphragm 76 during deflection thereof. Whereby, actuator 92 and cartridge striker 98 are simultaneously responsive to movement of the other.

Operation

In the embodiment illustrated in Figs. 1, 2 and 5, bolt actuator 48 and cartridge striker member 38 are placed in their rearward positions in bolt 22 so as to be in their proper relationship and then bore 24 or 26 is filled with hydraulic fluid 59 through port 28 up to the level of shoulder 32. Screw 34 is then installed and tightened against gasket 36 to seal port 28 liquid tight. In the embodiment illustrated in Figs. 3 and 4, passageway 64 is filled through hole 88 and then secured by screw 34. Bolt 22 is now ready for assembly in carrier 20 and the firing pin device including cartridge striker member 38, the column of hydraulic fluid 59 and actuator 48 performs as a conventional firing pin.

When breech member 18 is in battery position an hammer 56 is released to strike actuator 48, such actuator is impelled forwardly forcing the column of hydraulic fluid 59 ahead of seal 57 against seal 58 on cartridge striker member 38. Thereby, cartridge striker member 3 is impelled against the primer of cartridge 49 in chamber 14 of barrel 12 causing such cartridge to fire. In the resulting recoil of breech mechanism 18, retractor 40, a hereinbefore explained, actuates cartridge striker member 38 rearwardly with the column of hydraulic fluid 59 simultaneously transmitting such movement to actuator 48.

The embodiment illustrated in Figs. 3 and 4 functions the same way in bolt 22, the difference being that movement is transferred simultaneously between actuator 92 and cartridge striker member 98 by the responsive distensions of diaphragms 76 and 79 which transmit and respond to movement of hydraulic fluid 59 in passageway 64.

From the foregoing it is clearly apparent that there is here provided an improved firing pin device which is easily circumscribed around obstructions in the breech member, is easily adapted to offset mounting, permits unlimited length without undesirable effects, provides reduction in weight, is easily fabricated and is positive in operation.

Although a particular embodiment of the invention has been described in detail herein, it is evident that many variations may be devised within the spirit and scope thereof and the following claims are intended to include such variations.

I claim:

1. In a breech member for a firearm, a firing pin device including a reciprocably mounted cartridge striker member, a reciprocably mounted actuator member, a column of fluid, a first seal to inclose liquid tight the rear end of said actuator and said column of fluid, and a second seal to inclose liquid tight the front end of said column of fluid and to transmit movement between said column of fluid and said cartridge striker member.

2. The device of claim 1 with said first seal being secured to said actuator for reciprocation therewith, and said second seal being secured to said cartridge striker member for reciprocation therewith.

3. The device of claim 1 with said first seal being a diaphragm member cooperable with said actuator and said column of fluid for transmitting movement therebetween, and said second seal being a diaphragm member cooperable with said cartridge striker member and said column of fluid for transmitting movement therebetween.
